UNITED STATES PATENT OFFICE.

JOHN W. BROWN AND JAMES N. FITZSIMMONS, OF NEWARK, OHIO.

CORD HOLDER.

Application filed February 1, 1922. Serial No. 533,320.

To all whom it may concern:

Be it known that JOHN W. BROWN and JAMES N. FITZSIMMONS, citizens of the United States, residing at Newark, in the 5 county of Licking and State of Ohio, have invented certain new and useful Improvements in Cord Holders, of which the following is a specification.

This invention relates to an improved 10 twine or cord holder and has particular reference to that class of twine or cord holders which are adapted to be suspended from a relatively elevated support in order that the twine or cord may depend into convenient 15 reach of the user thereof without interfering in any way with the usual activities on the part of said user.

The primary object of the invention resides in the provision of a simple and improved 20 cord holder by means of which a ball or body of cord may be securely supported and wherein is embodied a curved rotatably mounted arcuate cord guide through which the cord passes, whereby 25 upon the drawing of the cord through the guide, the latter will be caused to rotate and remain in registration with the cord as the latter is drawn off of the main body thereof, said guide serving to prevent the 30 entanglement of the cord or the catching of the latter in the holder when the cord is under tensile stress.

Another object of the invention resides in a holder wherein is included a frame having 35 vertical sides and an oscillatory base plate pivotally secured to the lower ends of the sides, said plate being constructed to admit of convenience and facility in inserting or removing a ball of cord upon or from the 40 holder.

With these and other objects in view, as will appear as the description proceeds, the invention consists in the features of construction hereinafter described and claimed.

45 In the accompanying drawing:

Figure 1 is a perspective view showing the improved cord holder.

Figure 2 is a vertical longitudinal section taken therethrough.

50 Figure 3 is an edge elevation.

Figure 4 is a bottom plan view.

Referring more particularly to the details 55 of the invention, the numeral 1 designates our improved cord holder in its entirety.

This holder, in the specific embodiment thereof illustrated in the accompanying

drawing, comprises a frame preferably formed from sheet metal and generally of rectangular construction. This frame includes vertically extending spaced sides 2 60 connected by an integral horizontally extending top bar 3. The bar 3 is centrally provided with an eye 4 by means of which the holder may be suspended from a hook located in the ceiling or other elevated support. The bottom of the frame includes a pivotally movable base plate 5, arranged to extend between the lower ends of the sides 2 and in parallelism with the top bar 3. This base plate includes upstanding side wings 6, 70 which are pivotally secured as at 7 to the lower ends of the sides 2. Oscillation of the base plate is normally precluded by providing at least one of the wings 6 with an open ended slot 8, which receives the shank of a 75 bolt 9 rigidly carried by one of the sides 2. The outer end of the bolt 9 is formed to include a wing nut 10, which upon being tightened will securely hold the plate against oscillation about its pivot 7, but upon the 80 loosening of said wing nut, the plate may be oscillated so that a ball or cone of twine or cord 11 mounted upon the base plate, may be oscillated to assume a position clear of the sides 2 of the frame, permitting the said ball 85 or cone of twine or cord to be readily removed from or inserted upon the holder in operative relationship therewith.

In this instance, the base plate includes midway of its length a centrally located 90 upstanding U shaped stirrup 12, which constitutes a base for the reception of the lower open end of the sleeve or core 13, about which the cord or twine is wrapped. This sleeve is of conical form, and it will 95 be apparent that by pressing the same downwardly upon the stirrup 12, sufficient friction will be provided to prevent undue movement on the part of the ball of cord. Also connected with the stirrup 12 and extending vertically upward therethrough is a 100 tube 14, which is positioned in the cord and constitutes a support for the latter.

To permit of the withdrawal of the free end of the cord from the main body thereof 105 wrapped around the core 13, the present invention consists in providing the top of the tube 14 with a tubular rotatable guide 15. This guide as shown is of arcuate form and has its inner end provided with a collar 16 which is rotatably positioned upon the upper end of the tube 14, the said tube

being extended below the collar 16 so as to fit into the upper end of said tube to admit of the rotation of the guide about an axis defined by the upper end of the tube, 5 the collar 16 serving to limit inward movement of the guide into the tube and also to locate the outer end of the tube so that the latter will be substantially parallel with the upper end of the tube 14.

10 By this construction, it will be observed that after a body of cord has been properly positioned within the holder, the free end of the cord is trained through the rotatable guide 15 and also through the tube 14, the 15 lower end of the latter being open to permit the cord to pass vertically downward to any position where it may be needed. As the depending length of cord is drawn downwardly or used, the cord is unwound 20 from the main body or ball thereof, and this unwinding causes the guide to rotate closely following the cord as the latter is unwound from the ball or cone 11. This 25 results in the elimination of all binding or strain on the cord and enables the same to be delivered to the user with its full strength unimpaired. It will be noted particularly that the guide is of arcuate semi-

circular construction and includes no sharp edges whatever to catch or hold the latter 30 and thereby interfere with its free withdrawal.

What is claimed is:

1. In a cord holder, a frame including depending sides, a base plate connecting the 35 lower ends of said sides, wings provided upon the ends of said base plate, a pivotal connection between said wings and the sides of said frame, and a rigidly mounted cord receiving member arising centrally from 40 said base plate.

2. In a cord holder, a frame including depending sides, a base plate connecting the lower ends of said sides, wings formed upon the ends of said base plate, pivotal connections between said wings and the lower ends of said sides permitting of the oscillation 45 of said base plate, clamping means for retaining said base plate against oscillation, and a cord holding structure rigidly carried by said base plate and arranged to move in unison therewith.

In testimony whereof we affix our signatures.

JOHN W. BROWN.

JAMES N. FITZSIMMONS.
